(57) **CLAIM**

The ornamental design for a kitchen mitt, as shown and described.

DESCRIPTION

FIG. 1 is a perspective view of our new design for a kitchen mitt.

FIG. 2 is a front plan view of the kitchen mitt of FIG. 1.

FIG. 3 is a right side elevation view of the kitchen mitt of FIG. 1.

FIG. 4 is a top elevation view of the kitchen mitt of FIG. 1.

FIG. 5 is a left side elevation view of the kitchen mitt of FIG. 1.

FIG. 6 is a bottom elevation view of the kitchen mitt of FIG. 1; and,

FIG. 7 is a rear plan view of the kitchen mitt of FIG. 1.

In FIG. 1-7, the broken lines are included for the purpose of illustrating environment and form no part of the claimed design. The broken lines for the trademark "KG" are included for the purpose of illustrating environment and form no part of the claimed design. The broken line showing of the flap portion and of the stitching is for the purpose of illustrating portions of the kitchen mitt that form no part of the claimed design. The letter emblem, "KG" is a trademark of Browne & Co. Ltd.
